(57) **CLAIM**

I claim the ornamental design for a mobile phone, as shown and described.

DESCRIPTION

FIG. 1 is a front perspective view of a mobile phone, showing my new design;

FIG. 2 is a rear perspective view of the mobile phone shown in FIG. 1;

FIG. 3 is a front elevation view of the mobile phone shown in FIG. 1;

FIG. 4 is a rear elevation view of the mobile phone shown in FIG. 1;

FIG. 5 is a left side elevation view of the mobile phone shown in FIG. 1;

FIG. 6 is a right side elevation view of the mobile phone shown in FIG. 1;

FIG. 7 is a top plan view of the mobile phone shown in FIG. 1; and,

FIG. 8 is a bottom plan view of the mobile phone shown in FIG. 1.

The broken lines in the drawings depict portions of the mobile phone that form no part of the claimed design.

1 Claim, 8 Drawing Sheets
